UNITED STATES PATENT OFFICE.

CARSON C. COOK, OF CAMAS, IDAHO TERRITORY.

MAIL-BAG.

SPECIFICATION forming part of Letters Patent No. 393,360, dated November 27, 1888.

Application filed January 5, 1888. Serial No. 259,859. (No model.)

To all whom it may concern:

Be it known that I, CARSON C. COOK, of Camas, in the county of Bingham, Idaho Territory, have invented a new and useful Improvement in Mail-Bags, of which the following is a full, clear, and exact description.

My invention relates to an improvement in mail-bags, and has for its object to simplify the construction of the same, specially the locking devices and the formation of the bag at the mouth, and to provide a means whereby when the bag is locked matter cannot be abstracted therefrom without an indication appearing upon the surface of the bag denoting such an attempt, and wherein, also, the bag may be conveniently and expeditiously opened and closed.

The invention consists in the construction and combination of the several parts, as will be hereinafter fully set forth, and pointed out in the claims.

Reference is to be had to the accompanying drawings, forming a part of this specification, in which similar letters of reference indicate corresponding parts in all the figures.

Figure 1 is a partial perspective view of the bag open. Fig. 2 is a plan view of the same closed. Fig. 3 is a section through Fig. 1 taken partially on line *x x*. Fig. 4 is a partial elevation of the bag at the hinge, and Fig. 5 is a horizontal section on line *y y* of Fig. 4.

In carrying out the invention A represents a hinged frame, to which the upper or mouth portion of the bag is secured. The said frame consists of four sections, A', A², A³, and A⁴, of equal length, one section being connected to the other by a butt-hinge, *a*, two leaves of said hinge being made integral with one section and the interlocking leaf integral with the approaching section, as illustrated in Figs. 1 and 4. The pintle *a'* of each hinge is provided at the lower end with a vertical extension or lip, *b*, semicircular in cross-section, the convex surface whereof is made to face outward, which lip is designed to form a brace or stay for the corners of the bag, as will be hereinafter set forth. When the frame is opened, as shown in Fig. 1, the sections A' and A² will be parallel, and likewise the sections A³ and A⁴, presenting a rectangle. The body of the sections upon the outside and a slight dis-

tance from the hinge is provided with a longitudinal recess, *b'*, as shown in Fig. 5, into which recesses the upper edges of the material, constituting the outer portion, B', of the body B of the bag, is placed, the material being cut away at the hinges *a* to expose the same and permit perfect freedom of action, as illustrated at *b'* in Fig. 4. A strip of metal, C, is also inserted in the recess *b'*, bearing upon the body, which strip is preferably of a thickness sufficient to project outward flush with the sections at the hinge. The upper edges of the inner wall, C', of the body are laid upon the inner face of each frame-section, preferably flush with the top, and the inner and outer walls of body material, likewise the outer binding-plates, are secured to the various frame-sections by rivets passing through the same, as shown in Fig. 5, or in any other similar or approved manner. The inner body-strip is, preferably, of use as a continuous piece, covering the inner face of the hinges as well as the inner faces of the frame-sections, and as a means of preventing the cut-away portions of the outer body-strip from leaving the lower edge of the hinges. The two body-strips are held in close engagement with the pintle-extension *b* by a rivet passing through the said strip and lip, as shown in Fig. 4.

To the upper edges of the frame-sections A' and A² inwardly-projecting horizontal shields or cap-plates D are attached, beveled at opposing ends, as shown at *d* in Fig. 1, which beveled ends, when the bag is closed, are made to approach each other, as shown in Fig. 2.

Near the hinged connection of section A³ with section A' a longitudinal slot, *d'*, is produced in the former, and in the latter, also near the hinge, an aperture is produced, in which a key, D', is adapted to revolve, having an inner flat or winged head, *d*², and an outwardly-extending rectangular extremity, *d*³, upon which extremity one end of a hinged hasp, D², is secured, which hasp is adapted to carry the station-card, and is provided at its unattached end with a longitudinal slot, *e*, adapted to engage a staple, E, fastened to the inner face of the frame-section A² near its connection with the section A⁴, as will be hereinafter set forth. In the said frame-section A⁴, near its union with

section A^2 , a longitudinal slot, h , is made, having a central transverse segmental groove produced in its upper and lower walls, which slot h is purposed to receive the head of the key D' . When the bag is opened and the hasp is allowed to hang perpendicularly downward, as shown in Fig. 1, the head of the said key assumes a horizontal position parallel with the upper edge of the section A' .

10 The operation of closing and locking the bag is as follows: The sections A' and A^3 are unitedly folded against the sections A^2 and A^4 , the four respective sections in the order named in process of folding assuming straight lines. 15 When the said sections are brought in contact with each other, the shield or cap integral with section A' covers section A^4 and the shield integral with section A^2 the section A^3 . In so doing the beveled ends of the caps or shields 20 abut. Thus the upper edge of the bag is composed of virtually one piece of metal. As the bag is closed, the head of the key D' passes through the slot h beyond the section A^4 , and the staple E enters and projects out from the slot d' . The hasp D^2 is now brought to a horizontal position and made to engage the staple E through the slot e , whereupon any approved 25 form of lock is passed through the staple and secured. The act of bringing the hasp to a horizontal position causes the head of the key D' to turn and assume a vertical position or a 30 position at right angles to the section A' . Thus a second and secure lock is provided.

Upon the various sections the usual hanging or hand rings may be secured.

35 Having thus described my invention, what I claim as new, and desire to secure by Letters Patent, is—

1. In a mail-bag, the combination, with the 40 body, consisting of the spaced inner and outer walls, B' and C' , of the hinged frame-sections A' , A^2 , A^3 , and A^4 , and a lip or projection, b , projecting downward from the pintles of the hinges between the walls B' and C' and secured 45 thereto, substantially as shown and described.

2. In a mail-bag, the combination, with the body consisting of the spaced inner and outer walls, B' and C' , and the hinged upper frame-sec-

tions, A' , A^2 , A^3 , and A^4 , secured to said body having the pintles of the several hinges provided with a downwardly-projecting lip secured between the said body-walls, of the horizontal shields or cap-plates D , secured to the sections A' and A^2 , having opposite beveled ends, and means, substantially as shown and 55 described, for locking said sections, as and for the purpose herein set forth,

3. In a mail-bag, the combination, with the body consisting of the spaced inner and outer walls, B' and C' , the hinged upper frame-sections, A' , A^2 , A^3 , and A^4 , secured to said body, the section A^4 having a longitudinal slot, h , produced therein, the section A^3 having a horizontal slot, d' , and the section A^2 provided with a staple upon its inner face adapted to 60 enter the slot d' , and a lip projecting downward from the hinge-pintles and secured to the body between the walls, of a pin turning in the section A' , provided with a flattened inner head adapted to enter the slot h , a hasp, D^2 , attached to the outer end of said pin adapted to engage the staple, and a horizontal shield or cap integral with the sections A' and A^2 , all 65 adapted to operate as and for the purpose 70 herein set forth.

4. In a mail-bag, the combination, with the body consisting of the spaced inner and outer walls, B' and C' , the hinged upper frame-sections, A' , A^2 , A^3 , and A^4 , provided with an outer longitudinal recess, b , in which the outer 80 body-wall is secured, a plate, C , fitting in said recess and clamping the body, and a lip, b , concave in cross-section, integral with the pintles of the respective hinges, extending downwardly between the walls B' and C' and secured thereto, of the horizontal shields or cap-plates D , attached to the frame sections A' and A^2 , having opposite beveled ends, and means, substantially as described, for locking the frame-sections, as and for the purpose 85 90 herein set forth.

CARSON C. COOK.
